UNITED STATES PATENT OFFICE.

BENJAMIN F. GREGORY, OF STERLING, ILLINOIS.

ARTIFICIAL-STONE DIVIDER.

SPECIFICATION forming part of Letters Patent No. 635,096, dated October 17, 1899.

Application filed August 3, 1898. Serial No. 687,667. (No model.)

To all whom it may concern:

Be it known that I, BENJAMIN F. GREGORY, a citizen of the United States, residing at Sterling, in the county of Whiteside and State of Illinois, have invented certain new and useful Improvements in Artificial-Stone Dividers; and I do declare the following to be a full, clear, and exact description of the invention, such as will enable others skilled in the art 10 to which it appertains to make and use the same, reference being had to the accompanying drawings, and to the figures and letters of reference marked thereon, which form a part of this specification.

15 My invention pertains to the manufacture of artificial stone, and relates, more especially, to the construction of artificial-stone sidewalks. In the manufacture of such walks it is necessary to make the stone in separate 20 blocks or squares, so as to resist the action of the weather thereon and prevent injury to the walk through the expansion or contraction of the stone. It is usual to outline the walk by running timbers or stringers along 25 either side thereof parallel with and distant from each other the width of the proposed walk. Between these stringers the walk is then constructed by putting in alternate blocks, which are filled in after the first series 30 of blocks has set or hardened, the adjacent blocks being thus rendered independent of one another. In forming the first series of blocks the form of the block has heretofore been completed by placing cross-pieces 35 of wood, equal in length to the width of the walk, distant from each other the length of the block to be formed. Before the alternate spaces were filled in these cross-pieces were removed. By the use of my device these 40 cross-pieces, of which quite a number were required, are done away with, and the construction of the walk is rendered continuous, instead of it being necessary to build one-half of the walk and then go back and complete it, as heretofore, whereby considerable 45 time was lost. By the old process after the second series of blocks was constructed the contiguous blocks were separated by running a trowel between them; but this was often improperly done, resulting in a cracking of the walk. After the top dressing was on it was impossible to locate the joints be-

tween the stones unless marks had been previously made upon the side stringers; but these marks were often improperly placed and often omitted through carelessness. By the use of my invention this difficulty is obviated, as my device not only operates to complete and strengthen the form, but efficiently insulates or separates the contiguous blocks.

In the drawings, Figure 1 is a side elevation of my invention when in use. Fig. 2 is a plan view thereof.

1 1 represent the stringers which constitute the sides of the form, held temporarily in place by small stakes 2 2.

3 is a metallic plate or blade, preferably of steel, equal in length to the width of the proposed walk and provided at the ends with 70 the prongs 4, adapted to impinge the inner faces of the stringers 1 and prevent a movement of the plate 3 when in position. At each end of the plate 3, having longitudinal play on the upper edge thereof, are movable 75 braces 5 5, loosely held in place by the loops or guides 6 6, rigidly secured to the plate 3. The outer end of the brace 5 is projected downwardly at right angles to the brace into the hook 7, provided with prongs 8 and 80 adapted to embrace the outer face of the stringer 1.

9 is a lever pivotally secured to the plate 3, as at a, and provided with a pawl 10, adapted to engage the ratchet 11 on the upper edge 85 of the brace 5. The lever 9 is also provided with a longitudinal slot 12, loosely engaging the pindle 13, secured to the brace 5.

In operation two of my devices are placed in position between the stringers 1 and such 90 distance apart as it is desired to make the block of stone. By throwing the levers 9 inward the stringers 1 are drawn toward each other, the plate 3 and brace 5 clamped or locked together by means of the pawl 10 and 95 ratchet 11, and a rigid and inflexible form provided for the reception of the material. The plate 3 also establishes the width of the walk.

In the construction of artificial-stone walks 100 after the foundation is prepared the walk proper is usually formed of two layers, the lower or main layer being composed of a mixture of cement and coarse gravel or broken

stone and the top layer or surface of cement and sand.

If the contiguous blocks of the lower layer or grout are well separated, it is sufficient for 5 the preservation and permanence of the walk, and in the use of my invention, after the lower layer is in position and thoroughly tamped, the instrument nearest that end of the walk which is first constructed, is removed by releasing the pawls 10 and slipping the plate 3 upward from between the material, replacing such plate in position for the next block. The withdrawal of the plate 3 leaves a well-defined interval between the blocks of stone 15 which it separated when in position.

By reason of the binding of the form together with my invention a less number of small stakes 2 is required, resulting in a considerable saving in material, labor, and time. 20 What I claim as my invention, and desire to

secure by Letters Patent of the United States, is—

1. In an artificial-stone separator, the combination of the plate 3; movable braces 5, adapted to adjustably engage the plate 3 at 25 its ends; and having hooks 7, substantially as shown and set forth.

2. In an artificial-stone separator, the combination of the plate 3, provided in its ends with the prongs 4; braces 5, having the hooks 30 7 at their outer ends, said hooks 7 being further provided with inturned prongs 8; and means to secure the braces 5 and plate 3 together, substantially as shown.

In testimony whereof I affix my signature 35 in presence of two witnesses.

BENJAMIN F. GREGORY.
